LINE STOP FOR TYPOGRAPHICAL CASTING MACHINES

Charles G. English, Corpus Christi, Tex., assignor to Mergenthaler Linotype Company, a corporation of New York

Application July 17, 1953, Serial No. 368,758

8 Claims. (Cl. 199—49)

This invention relates to typographical casting machines of the general organization represented in U. S. Letters Patent to O. Mergenthaler, No. 436,532, wherein circulating matrices are released from a magazine in the order in which their characters are to appear in print and then composed in line in a vertically movable assembler. After composition of the line, the assembler is raised and the line transferred therefrom into a vertically movable transporter, or so-called "first elevator," which thereupon descends to position the line between a pair of vise jaws which clamp and hold the line in front of a mold for the casting of the type bar or slug. After the slug casting operation, the transporter rises to its uppermost level and the matrices are transferred to a so-called "second elevator" for delivery to the distributing mechanism, by which the matrices are separated and returned to the magazine from whence they started.

When received by the first elevator, the composed matrix line is confined endwise between a so-called "line stop," carried by the first elevator, and a pair of retaining pawls located at the receiving end of the elevator, the line stop being adapted and arranged to prevent twisting or displacement of the leading matrix in the composed line and the retaining pawls being adapted and arranged to prevent twisting or displacement of the last or terminal matrix in the composed line.

The line stop normally occupies a position to the extreme right of the first elevator so as to engage the leading matrix of the composed line as the latter enters the first elevator, the composed line pushing the line stop to the left for a distance corresponding to the length of the line. Later, when the composed line is removed from the first elevator, the line stop is restored automatically to its initial or line receiving position. It is in this way that the line stop automatically accommodates itself to lines of different length, functioning always to give support to the leading matrix of the line.

The most improved line stop now in use is the one shown in the Mead Patent No. 2,121,975, dated June 28, 1938. As therein shown and described, the line stop comprises a pair of parallel rails slidably arranged in the matrix grooves of the first elevator, these rails being formed on their upper edges with ribs which slide in the spaceband grooves of the first elevator. The rightward ends of the rails are, of course, arranged in transverse alignment and constitute abutments for contact with the leading matrix of the composed line. At their leftward ends, the two rails are connected by a bridge plate which causes them to move in unison and which exerts a separating force upon the rails to hold them in frictional engagement with the matrix and spaceband grooves as the line stop is pushed to the left by the composed line as it enters the first elevator. It is this frictional engagement which is relied upon to allow the line stop to accommodate itself automatically to lines of different lengths.

As also shown and described in the Mead patent, the two side rails are also provided along their upper edges with spring plates which contact with the upper walls of

2

the spaceband grooves and thus exert a further braking influence upon the line stop in its receding movements.

The manufacture of the foregoing line stop is quite costly, requiring at least ten different machining operations to produce it. Moreover, the performance of the line stop in actual use has not been entirely satisfactory. For example, after a certain period of use, the line stop loses its frictional drag and oftentimes overruns its proper line supporting position. This is especially true in machines equipped with quadding and centering devices, wherein the right hand jaw, when moved to the left for quadding or centering, exerts a sharp propelling influence upon the line and through it the line stop. Moreover, it not infrequently happens that the line stop will fall out of position altogether, due to the loss of tension exerted by the connecting plate.

The present invention is directed to an improved line stop and one which may not only be manufactured at low cost, but one which gives more satisfactory performance in use. In the specific embodiment illustrated, the improved line stop comprises a pair of thin and narrow abutment plates shaped and spaced for sliding movement in the matrix grooves of the first elevator and an elongated spring wire element which is arranged to slide in the spaceband grooves of the first elevator, this U-shaped wire element having the free ends of its two leg portions united to the abutment plates and its bent or loop connecting portion being tensioned to exert the desired frictional engagement with the matrix grooves. The improved line stop is also provided with an actuating plate, which may be united with one of its leg portions, for automatic return to its initial position when the composed line is removed from the first elevator. The two abutment plates and the actuating plate may be separately manufactured and then welded to the wire element, which latter may consist of a straight round wire bent into U form, leaving a curved or loop connecting portion which produces the desired tension. It has been found that such a wire element will retain a set resiliency for much longer periods than possible with the old form of line stop and, moreover, permits the tension to be varied to suit different conditions by bending the wire by hand at the closed or loop end.

Referring to the drawings:

Fig. 1 is a front elevation of a portion of a typographical casting machine equipped with the improved line stop;

Fig. 2 is an enlarged elevational view, with portions broken away, of the upper line transfer slide which removes the composed line from the first elevator after the casting operation;

Fig. 3 is an end view, looking from the left, of the parts shown in Fig. 2;

Fig. 4 is an end view of the improved line stop, taken at the entrance end of the first elevator;

Figs. 5 and 6 are top plan and side views of the improved line stop;

Fig. 7 is a view similar to Fig. 2, but showing the improved line stop in modified form to cooperate with an upper transfer slide of a different form;

Fig. 8 is a top plan view of the parts shown in Fig. 7;

Fig. 9 is a perspective view of the modified form of line stop as it appears mounted in the first elevator.

In the operation of a Linotype machine the matrices X and spacebands Y are released from their respective magazines by the manipulation of a keyboard (not shown), and are composed in line in the usual manner in an assembler A. After the line has been composed, the assembler is raised to position the line between a pair of depending fingers B and C of a line delivery slide D which, thereupon, transfers the line through an intermediate channel E into a vertically movable line transporter or first elevator F. As the line delivery carriage

D banks against a fixed stop screw G, which limits the movement of its active stroke, the composed line will be located in the first elevator F as indicated by the dotted lines in Fig. 1, where it is restrained against endwise displacement by the improved line stop, to be described, and a pair of resilient pawls, one of which is shown in Fig. 9 and designated H. As before explained, the leading matrix of the composed line will be held upright by contact with the line stop while the end or terminal matrix of the line will be maintained upright by the pawls H.

After the composed line has been transferred into the first elevator F, the latter descends to position the line between a pair of vise jaws I and J preparatory to the casting operation. After the slug is cast, the first elevator rises to its uppermost position, as shown in Fig. 2, the line stop and the retaining pawls meanwhile acting to prevent displacement of the matrices at the opposite end of the line. As the first elevator reaches its uppermost position, a reciprocatory transfer slide K removes the line therefrom and delivers it into an upper transfer channel L. During such transfer the matrices of the composed line are threaded onto a ribbed bar M of a so-called second elevator, while the spacebands remain supported in the upper transfer channel for return to their storage magazine N. After the removal of the line therefrom, the first elevator returns to its original line receiving position as shown in Fig. 1.

All of the foregoing parts and their mode of operation are or may be the same as embodied in the commercial Linotype machine and require no further explanation.

It may here be pointed out that the front and back jaws 1 and 2 of the first elevator F (see Fig. 4) are formed with opposed grooves 3 which receive and give support to the matrices X by their upper projecting ears, as well as with opposed grooves 4 which receive and give support to the spacebands by their narrower upper ears, all in the customary way.

Referring now to the improved line stop, reference is first made to the form shown in Figs. 1 to 6. It comprises basically four elements, namely, two narrow and thin abutment plates 5 and 6, an elongated U-shaped spring wire element 7, and a long and thin actuating return plate 8. The two abutment plates are shaped and arranged to fit slidably in the matrix grooves 3 of the first elevator, while the U-shaped spring element is shaped and arranged to fit slidably in the spaceband grooves 4, all as clearly shown in Fig. 4. The actuating plate 8, like the abutment plate 6, is shaped and arranged to fit slidably in the matrix groove formed in the rear elevator jaw 2 (see Fig. 2). The wire element is made from a straight piece of round wire, being intermediately bent or looped at 7^a to provide two long and parallel leg portions 7^b. At their free ends the two leg portions 7^b are united, as by welding, to the outer faces of the abutment plates 5 and 6, and the rear leg portion is similarly united to the actuating plate 8, which latter it may be noted presents a lower leftward extension 8^a for engagement with the pusher K¹ attached to the upper transfer slide K.

The improved line stop may be inserted into the first elevator from the left in the usual way, a stop 9 on the rear elevator jaw 2 (see Figs. 1 and 2), by engagement with the extension 8^a of the return plate 8, locating the abutment plates 5 and 6 at the entrance end of the first elevator in position to contact the leading matrix of a composed line as it is transferred into the elevator by the line delivery carriage D. The bent or looped portion 7^a of the wire element may be tensioned or stressed to exert whatever separating force may be necessary to produce the desired frictional drag upon the abutment plates as they are pushed ahead or to the left in the matrix grooves by the entering line. An additional fric-

tional drag will also be exerted by the slideable engagement of the leg portions 7^b in the spaceband grooves. As can readily be understood, the spring wire element will retain its resilient properties for a long period of time but if and when it becomes necessary to alter the frictional drag, this may be accomplished by manipulating the bent or looped portion 7^a.

In Fig. 1, the improved line stop is shown by the full lines in its normal line receiving position and by the dotted lines in its retracted or line supporting position. In Fig. 2, the line stop is shown as having been restored to its normal line receiving position by the transfer of the composed line from the first elevator into the upper transfer channel.

The form of the line stop shown in Figs. 7 and 8 differs from that above described only in respect to the form and location of the return plate. This plate, as shown in Fig. 9, is formed integrally with the rear abutment plate 6, rising therefrom in the form of a hook 10 slidably engaged in a groove 11 formed in the upper edge of the rear elevator jaw 2. This hook-shaped return plate 10 is positioned to be engaged by a pusher K² carried by the upper transfer slide K.

In some machines, the upper transfer slide is of the form shown in Figs. 1 to 6 and in other machines of the form shown in Figs. 7 to 9. This will explain the need for two different forms of the improved line stop.

It will now be appreciated that the improved line stop may be manufactured at a fraction of the cost of any of the prior art line stops, that it will possess a much longer life in service, and that its behavior will be more satisfactory notwithstanding its simplified form.

The details of the invention may be changed without departing from the spirit of the invention, and hence it should be understood that the invention is not limited to any specific form of embodiment except insofar as such limitations are specified in the appended claims.

What is claimed is:

1. A line stop for the first elevator or line transporter of a typographical casting machine, said transporter being formed in its opposite side walls with a pair of opposed horizontally disposed matrix supporting grooves as well as with a distinct pair of opposed horizontally disposed spaceband supporting grooves, which spaceband supporting grooves are of less vertical height and are more widely spaced apart than the matrix supporting grooves but are located within the vertical limits of said grooves, characterized in that said line stop comprises an elongated, U-shaped resilient member shaped and spaced for a sliding movement in the spaceband supporting grooves, and a pair of thin and narrow abutment plates shaped and spaced for a sliding movement in the matrix supporting grooves, said abutment plates being made separate from but united to the two leg portions of the U-shaped resilient member at its open end, and said U-shaped resilient member being stressed at its closed end to exert a separating force upon its two leg portions when the line stop is inserted into the line transporter and thus to hold the abutment plates under lateral pressure in frictional face contact with the vertical walls of the matrix supporting grooves for braking purposes.

2. A line stop according to claim 1, wherein the separating force exerted upon the two leg portions of the U-shaped resilient member when the line stop is inserted into the line transporter also holds said leg portions under lateral pressure in frictional contact with the vertical walls of the spaceband supporting grooves for additional braking purposes.

3. A line stop according to claim 1, wherein the U-shaped resilient member is constituted by a long spring wire bent or looped into U-form and with the two leg portions united to the outer faces of the abutment plates.

4. A line stop according to claim 1 comprising, as an additional element, an actuating plate shaped and spaced 75 for a sliding movement in one of the matrix supporting

grooves, said plate being made separate from but united along its outer face to one of the leg portions of the U-shaped resilient member.

5. A line stop according to claim 4, wherein said actuating plate forms part of one of the abutment plates at the free open end of the U-shaped resilient member.

6. A line stop according to claim 4, wherein said actuating plate is united to the leg portion of the U-shaped resilient member in the region of its closed end and extends outwardly beyond the same.

7. In a typographical casting machine, the combination of a first elevator or line transporter formed in its opposite side walls with a pair of opposed horizontally disposed matrix supporting grooves as well as with a distinct pair of opposed horizontally disposed spaceband supporting grooves, which spaceband supporting grooves are of less vertical height and are more widely spaced apart than the matrix supporting grooves but are located within the vertical limits of said matrix supporting grooves, means for delivering the composed line of matrices and spacebands 20 into the transporter and means for subsequently removing the composed line from the transporter, and a line stop mounted in the transporter and normally positioned in the path of the incoming line and adapted to be returned automatically to its initial position by the line removing 25 means, said stop comprising an elongated U-shaped resilient member shaped for a sliding movement in the space-

band supporting grooves, and a pair of thin and narrow abutment plates shaped and spaced for a sliding movement in the matrix supporting grooves, said abutment plates being made separate from but united to the two leg portions of the U-shaped resilient member at its open end, and said U-shaped resilient member being stressed at its closed end to exert a separating force upon its two leg portions and thus hold the abutment plates under lateral pressure in frictional face contact with the vertical walls of the matrix supporting grooves for braking purposes.

8. A combination according to claim 7, wherein the line stop also comprises an actuating plate made separate from but united to one of the leg portions of the U-shaped resilient member and arranged to be engaged by a part 15 of the line removing means.
